The schedule referred to in these Letters Patent and making part of the same.

To all whom it may concern:

Be it known that I, David Hathaway, of the City of Troy,

original Design for a Parlor-cook Stove, called the "Spartan"; and I do hereby declare that
the following is a full and exact description of the same, reference being had to the annexed
photograph making part of this Specification.

My said ornamental design consists of a cluster of grapevines, a, hung
at the top, and a shield, b, placed at the bottom, of each of the upper front doors; a shield
piece, c, set upon a bracket, covered by a confined curtain, d, upon each of the lower front
doors; a semi-circular arch, e, with pendants, f, over niches, g, on the door, or upper part,
of each end-plate, and a censer, h, under a gothic arch, i, on the lower part of the same,
the whole being formed and arranged together substantially as shown in the annexed
photographic drawing.

What I claim as my invention or production and desire to secure
by Letters Patent is the ornamental design for a parlor-cook stove herein described and re-
presented in the annexed photographic drawing.
